UNITED STATES PATENT OFFICE.

WILLIAM S. TRASK, OF NEW BRITAIN, CONNECTICUT, ASSIGNOR TO P. & F. CORBIN, OF NEW BRITAIN, CONNECTICUT, A CORPORATION OF CONNECTICUT.

DOOR-KNOB COMPENSATOR.

No. 922,359.

Specification of Letters Patent.

Patented May 18, 1909.

Application filed September 12, 1908. Serial No. 452,719.

To all whom it may concern:

Be it known that I, WILLIAM S. TRASK, a citizen of the United States, residing at New Britain, county of Hartford, State of Connecticut, have invented certain new and useful Improvements in Door-Knob Compensators, of which the following is a full, clear, and exact description.

My invention relates to improvements in means for mounting door knobs and the spindles therefor upon the door, and the object thereof is to provide compensating means for taking the end thrust of the knobs and spindle and to hold the spindle against loose longitudinal play.

A further object is to provide in the construction above outlined means for supporting the spindle at points removed from the lock, to obviate any rocking movement of the spindle when in position.

A further object is to so construct and arrange devices of this character whereby friction between the knobs and spindles and their supporting parts will be reduced to a minimum.

With these objects in view, the invention consists in the construction and arrangement of parts, a preferred embodiment of which is illustrated in the accompanying drawings, in which—

Figure 1 is a sectional view showing the knobs and spindle assembled upon the door. Fig. 2 is a detail view of parts shown in Fig. 1. Fig. 3 is also a detail view of parts shown in Fig. 1.

In the embodiment of my invention herein selected for illustration, the lock case 1 is indicated in section mounted in a mortise 2 of the door 3, the latter being indicated in dotted outline. Passing through the lock hub 4, which is rotatably mounted in the lock case 1, is the knob spindle 5, which may be of usual rectangular cross section and which has secured thereon in any suitable manner, as by the usual screws, knobs 6. Upon the spindle 5 are slidably mounted flat washers 7, said washers being shown in detail in plan and edge view in Fig. 3, and said washers are preferably provided with apertures 8 corresponding in outline to the cross section of the spindle 5. These washers 7, as will be noted from an inspection of Fig. 1, bear against the opposite ends of the lock hub 4 of the lock and are held thereby out of contact with the sides of the lock case. Also

mounted upon the spindle 5 are the short sleeves 9 shown in detail in Fig. 2, each of which is apertured at 9^a to fit the spindle and has a flange 10 at one end which is normally located (when all the parts are assembled) just inside of and slightly removed from the escutcheon plate 11. Between each washer 7 and the sleeve 9 and surrounding the spindle 5 is an expanding device, such as a coil spring 13, which serves to press apart washer 65 and sleeve. When all the parts are assembled, the outer ends of the sleeves 9 press against the inner ends of the knob shanks.

By the construction above described, it will be noticed that the action of the springs 13 between the washers 7 and sleeves 9 will serve to maintain the latter elements against the lock hub and the knob shanks respectively, whereby loose end play of the knobs and knob spindle will be effectually prevented. Furthermore, inasmuch as the washers, sleeves and springs are all mounted to rotate with the knob spindle, and as the latter is mounted within the lock hub 4, which is adapted to rotate in the lock case, substantially all friction opposing the rotation of the knobs and spindle is eliminated. The apertures in the escutcheon plates within which the sleeves 9 are seated are of such size as to afford an easy fit and bearing for said sleeves whereby the spindle is rotatably supported at these points in addition to its support within the lock hub 4. These three comparatively widely separated bearing points of the spindle effectually prevent any rocking movement thereof.

Another distinct advantage of combining in this particular connection a spring compensating means is that it performs a second function of forcing knobs 6 longitudinally on spindle 5 in such manner as to set up friction between the knob retaining screws by which the knobs are secured to the spindle thus preventing said screws from working loose and falling out. In common practice, the knob spindles are provided with a series of screw passages to enable the knobs to be applied to doors of different thickness, that particular screw passage most conveniently located with reference to the screw passage in the knob shank being the one selected.

While I have here shown and described the particular embodiment of the device, it is to be understood that the same may be altered in detail and arrangement of parts without departing from the spirit and scope thereof.

What I claim is:

1. In a device of the character described, the combination with a lock hub, a knob spindle slidable therein but non-rotatable relatively thereto, a knob adjustably mounted upon said spindle and compensating means between said knob and said hub comprising means for exerting end pressure between said knob and hub tending to force said parts away from each other, and a spacing sleeve between said means and said knob substantially as and for the purpose described.

2. In a device of the character described, the combination with a lock hub, a knob spindle slidable therein but non-rotatable relatively thereto, a knob adjustably mounted upon said spindle and compensating means between said knob and said hub comprising a coil spring surrounding the spindle for exerting end pressure between said knob and hub tending to force said parts away from each other, and a spacing sleeve between said spring and said knob substantially as and for the purpose described.

3. In a device of the character described, a lock hub, a knob spindle mounted therein, and two opposed yielding compensating devices interposed between the knobs carried by said spindle and bearing against opposite ends of said hub and rotatable therewith.

4. In a device of the character described, a lock hub, a knob spindle mounted therein, knobs thereon, two compensating devices mounted on said spindle and arranged be-

tween opposite ends of said hub and the knobs, all of said parts adapted to rotate with said spindle.

5. In a device of the character described, a lock hub, a knob spindle mounted therein, 40 escutcheon plates surrounding said spindle, and compensating devices interposed between the ends respectively of said hub and the knobs carried by said spindle and rotatable therewith, said devices having bearings 45 for rotation in the opposite escutcheon plates respectively said bearings supporting said spindle for side displacement.

6. In a device of the character described, a lock hub rotatable in its lock case, a spindle 50 carried thereby, a compensating device interposed between said hub and a knob carried by said spindle, said device comprising a washer bearing on said hub, a sleeve adjacent the knob and having a bearing in an 55 escutcheon plate surrounding said spindle, and a spring interposed between said washer and sleeve.

7. In a device of the character described, a lock hub, a spindle carried thereby, washers mounted upon said spindle, and bearing upon the respective ends of said hub, sleeves also mounted upon said spindle adjacent the knobs carried thereby and springs interposed between each washer and sleeve respectively. 60 65
